UNITED STATES PATENT OFFICE.

JOHN O. McKEAN, OF WESTFIELD, MASSACHUSETTS, ASSIGNOR TO FOSTER MACHINE COMPANY, OF WESTFIELD, MASSACHUSETTS, A CORPORATION OF MASSACHUSETTS.

SLUB CATCHER.

Application filed October 28, 1922. Serial No. 597,604.

To all whom it may concern:

Be it known that I, JOHN O. McKEAN, a citizen of the United States, and resident of Westfield, in the county of Hampden and 5 State of Massachusetts, have invented a new and useful Improvement in Slub Catchers, of which the following is a specification.

The object of my invention is to provide a novel form of slub catcher having a yarn 10 clearing hole which will be readily adjustable for yarns of various sizes; through which the yarn may be easily and quickly threaded; and which will not chafe nor scrape the 15 yarn.

My invention comprises a slub catcher having two coacting members forming between them a yarn clearing hole, one of the members being movable to change the size 20 of the hole and also movable to open the hole, means being employed for yieldingly holding the members together.

My invention more particularly comprises a structure in which one of the members has a slot, the walls of which form a portion of 25 the yarn clearing hole and the other member has a rotatively adjustable disc with its peripheral surface disposed lengthwise along said slot to form the remaining portion of the hole, said peripheral surface being graduated or tapered circumferentially so that 30 the size of the yarn clearing hole may be readily changed by a rotative adjustment of the disc; means being employed, such for instance by making the slot in one of the 35 members inclined for deflecting the yarn as it enters the slub catcher to require the movement of the other member bodily to open the hole for the proper threading of the 40 yarn.

Practical embodiments of my invention are represented in the accompanying drawings, in which—

Fig. 1 represents in top plan a device for 45 guiding, tensioning and clearing yarn with my invention applied thereto.

Fig. 2 represents a side view of the same.

Fig. 3 represents a front view.

Fig. 4 represents a detail section taken in 50 the plane of the line IV—IV of Fig. 1.

Fig. 5 represents a detail section taken in the plane of the line V—V of Fig. 1.

Fig. 6 represents a detail section taken 55 in the plane of the line VI—VI of Fig. 2.

Fig. 7 represents a detail enlarged section,

showing the yarn clearing hole adjusted for 55 a yarn of one size, the divergent walls of the slot being shown straight.

Fig. 8 represents a similar view, showing 60 the yarn clearing hole adjusted for a yarn of a larger size.

Fig. 9 represents a similar view, showing 65 the divergent side walls of the slot as being convex.

Fig. 10 represents a similar view, showing 70 the divergent side walls of the slot as being concave.

Fig. 11 represents a similar view, showing 75 the graduated peripheral surface of the movable member as comprising a circumferential slot with divergent side walls, to form with 80 the slot in the other member a rectangular hole, as distinguished from the triangular holes shown in the other views.

The bracket as herein constructed comprises the longitudinal portion 1 terminating 75 at one end in a turned-back portion 2, and at its other end in upwardly and outwardly inclined ears 3 and 4. A loop is formed at one side of the portion 1 of the bracket, which loop comprises the lateral branches 5 and 6, connected by the longitudinal branch 7. An arm 8 projects forwardly from the lateral branch 6 to form a suitable yarn support in the tension device.

A pin 9 uprises from the arm 8, upon 85 which pin is loosely mounted the weighted tension disc 10, between which disc and the top surface of the arm 8 the yarn is passed on its way to the slub catcher to be herein-after described.

The lug 11 projects laterally from the portion 1 of the bracket in the opposite direction from the branch 6 of the loop, into 90 which lug is screwed the pivot pin 12 on which a vertically yielding lateral swinging 95 guard 13 is pivoted. The vertically yielding movement of this guard is provided for in the present instance by a recess 14, within which there is located a coil spring

15, interposed between the bottom of the recess and the head of the pin 12. The outer end of this washer guard 13 is provided with a portion 16 which projects over the weighted washer 10 and on top of the pin 9 of the tension device when the guard 100 is in its operative position.

Means are provided for yieldingly holding 105 the guard in its operative position,

which means is herein shown as a notch and projection connection between the guard and the turned-back portion 2 of the bracket; the notch 17 being formed in the guard and 5 the projection 18 being formed on the said turned-back portion.

When the guard is swung back out of its operative position, the weighted washer 10 may be readily removed from the pin 9.

10 The slub catcher for the yarn comprises two coacting members, one having a slot with walls forming a portion of the yarn clearing hole, and the other with a graduated surface forming the remaining portion 15 of the said yarn clearing hole.

In the present instance the fixed member is the branch 5 of the loop hereinbefore described, which branch is shown as provided with an outwardly and downwardly inclined 20 slot 19 across its upper face, the divergent walls of which slot form two sides of a triangular yarn clearing hole. The other member of the slub catcher is herein shown as comprising a two armed lever 20, pivoted between the upwardly and outwardly inclined lugs 3 and 4 of the bracket on an outwardly and downwardly inclined pivot screw 21. One arm of this lever may be provided with a handle 22 for manipulating 25 the lever. The other arm of the lever is provided with a rotatively adjustable disc having its circumferentially graduated or tapered peripheral surface 24 disposed lengthwise along the outwardly and downwardly inclined slot of the other member with the side edges of the disc in contact with the divergent walls of said slot, to form the third side of the triangular yarn 30 clearing hole. The disc 23 is loosely mounted on the pivot screw 25 which passes axially through the disc into the said lever, so that the disc 23 will center itself in the slot of the other member, forming a complete 35 hole. The means which I have shown for locking the disc in its rotatively adjusted position is shown as a removable pin 27 passing through one of a concentric series of holes 26 in the disc, into the hole 28 in the lever 20. A set screw 29, having its head 40 countersunk in a recess 31 of an upris- 30 ing lug 32, serves to engage the pin 27 to lock it against unintentional removal.

When it is desired to rotatively adjust the disc 23 to change the size of the yarn clearing hole, the set screw 29 is loosened by a special tool, the pin 27 is then inserted through the proper hole in the disc and into the lever, and the set screw 29 is then tightened to lock the parts in their adjusted position.

Means are employed for yieldingly holding the coacting members of the slub catcher together, which means is herein shown as a coil spring 33, extending between the bracket 60 and the lever. To open the yarn clearing

hole to permit the threading of the yarn, the disc may be lifted out of the slot by depressing the handle 22 of the lever 20 against the tension of the spring 33.

It will be understood that the rotative adjustment of the disc will change the size of the yarn clearing hole because of the graduated or tapered peripheral surface of the disc, to suit yarns of various sizes; this adjustment of the size of the yarn clearing hole being of a very fine degree, so as to ensure the best results in clearing the yarn. It will also be seen that only one yarn clearing hole may be provided, the two coacting members of the slub catcher being capable of adjustment to change the size of the hole, to suit yarns of various sizes and also being capable of movement to open the hole to permit the threading of the yarn.

The reason for the provision of a curved surface on one of the members coacting with the slot in the other member, is to allow the yarn to enter into the slub catcher without scraping or chafing the yarn as would be the case where a square surface is used. 90 When either a thin blade or a square or rectangular block is used, an edge is provided which comes in contact with the yarn on the entering side of the slub catcher. This is avoided in the present invention. 95

The reason for deflecting the yarn, in the present instance by inclining the slot outwardly and downwardly, is to compel the opening of the hole for the threading of the yarn through the slub catcher, if the disc is not raised to open the slot for threading the yarn, the yarn will be caught or wedged between one side of the disc and one side wall of the slot, and thus cause the yarn to break. It is therefore absolutely necessary to open the yarn clearing hole to properly thread the yarn through the slub catcher before the yarn can be slubbed, run or wound on the winder.

While I have shown the yarn clearing hole in several of the forms as triangular and in another form as rectangular in cross section, it is obvious that the cross section of the hole may be of any desired shape so long as it fills the requirements of the present invention.

It is also evident that various changes may be resorted to in the construction, form and arrangement of the several parts without departing from the spirit and scope of my invention, hence I do not wish to limit myself to the particular embodiments herein shown and described, but

What I claim is:

1. In slub catcher, two coacting members, one having a yarn receiving slot and the other a graduated surface disposed lengthwise along said slot to form a yarn clearing hole, the last named member being movable to bring different portions of said graduated

surface within said slot to change the size of the hole, said last named member being also movable to open the hole.

2. In a slab catcher, two coacting members, one having a yarn receiving slot and the other a graduated surface disposed lengthwise along said slot to form a yarn clearing hole, the last named member being movable to bring different portions of said graduated surface within said slot to change the size of the hole, said last named member being also movable to open the hole, said yarn receiving slot being inclined for deflecting the yarn as it enters the slot to require the opening of the hole for the proper threading of the yarn.

3. In a slab catcher, two coacting members, one having a yarn receiving slot and the other a graduated surface disposed lengthwise along said slot to form a yarn clearing hole, the last named member being movable to bring different portions of said graduated surface within said slot to change the size of the hole, said last named member being also movable to open the hole, and means for yieldingly holding the two members together.

4. In a slab catcher, two coacting members, one having a yarn receiving slot and the other a graduated surface disposed lengthwise along said slot to form a yarn clearing hole, the last named member being movable to bring different portions of said graduated surface within said slot to change the size of the hole, said last named member being also movable to open the hole, said yarn receiving slot being inclined for deflecting the yarn as it enters the slot to require the opening of the hole for the proper threading of the yarn, and means for yieldingly holding the two members together.

5. In a slab catcher, two coacting members, one having a yarn receiving slot and the other a curved graduated surface disposed lengthwise along said slot to form a yarn clearing hole, the last named member being rotatively adjustable to bring different portions of said curved graduated surface within said slot to change the size of the hole.

6. In a slab catcher, two coacting members, one having a yarn receiving slot and the other a curved graduated surface disposed lengthwise along said slot to form a yarn clearing hole, the last named member being rotatively adjustable to bring different portions of said curved graduated surface within said slot to change the size of the hole, the last named member being also bodily movable to open the hole.

7. In a slab catcher, two coacting members, one having a yarn receiving slot and the other a curved graduated surface disposed lengthwise along said slot to form a yarn clearing hole, the last named member

being rotatively adjustable to bring different portions of said curved graduated surface within said slot to change the size of the hole, the last named member being also bodily movable to open the hole, said yarn receiving slot being inclined for deflecting the yarn as it enters the slot to require the opening of the hole for the proper threading of the yarn.

8. In a slab catcher, two coacting members, one having a yarn receiving slot and the other a curved graduated surface disposed lengthwise along said slot to form a yarn clearing hole, the last named member being rotatively adjustable to bring different portions of said curved graduated surface within said slot to change the size of the hole, the last named member being also bodily movable to open the hole, and means for yieldingly holding the members together.

9. In a slab catcher, two coacting members, one having a yarn receiving slot and the other a curved graduated surface disposed lengthwise along said slot to form a yarn clearing hole, the last named member being rotatively adjustable to bring different portions of said curved graduated surface within said slot to change the size of the hole, the last named member being also bodily movable to open the hole, said yarn receiving slot being inclined for deflecting the yarn as it enters the slot to require the opening of the hole for the proper threading of the yarn, and means for yieldingly holding the members together.

10. In a slab catcher, two coacting members, one having a yarn receiving slot and the other provided with a disc having a graduated peripheral surface disposed lengthwise along said slot, forming a yarn clearing hole, said disc being rotatively adjustable to change the size of the hole.

11. In a slab catcher, two coacting members, one having a yarn receiving slot and the other provided with a disc having a graduated peripheral surface disposed lengthwise along said slot, forming a yarn clearing hole, said disc being rotatively adjustable to change the size of the hole and movable bodily to open the hole.

12. In a slab catcher, two coacting members, one having a yarn receiving slot and the other provided with a disc having a graduated peripheral surface disposed lengthwise along said slot, forming a yarn clearing hole, said disc being rotatively adjustable to change the size of the hole and movable bodily to open the hole, said yarn receiving slot being inclined for deflecting the yarn as it enters the slot to require the opening of the hole for the proper threading of the yarn.

13. In a slab catcher, two coacting members, one having a yarn receiving slot and the other provided with a disc having a

graduated peripheral surface disposed lengthwise along said slot, forming a yarn clearing hole, said disc being rotatively adjustable to change the size of the hole and movable bodily to open the hole, and means for yieldingly holding the members together.

14. In a slub catcher, two coacting members, one having a yarn receiving slot and the other provided with a disc having a graduated peripheral surface disposed lengthwise along said slot, forming a yarn clearing hole, said disc being rotatively adjustable to change the size of the hole and movable bodily to open the hole, said yarn receiving slot being inclined for deflecting the yarn as it enters the slot to require the opening of the hole for the proper threading of the yarn, and means for yieldingly holding the members together.

15. In a slub catcher, two coacting members, one having a yarn receiving slot and the other comprising a lever pivoted on an axis substantially parallel with said slot, and a disc pivoted to said lever and having a graduated peripheral surface disposed lengthwise along said slot to form a yarn clearing hole, said disc being rotatively adjustable to change the size of the hole.

16. In a slub catcher, two coacting members, one having a yarn receiving slot and the other comprising a lever pivoted on an axis substantially parallel with said slot, and a disc pivoted to said lever and having a graduated peripheral surface disposed lengthwise along said slot to form a yarn clearing hole, said disc being rotatively adjustable to change the size of the hole and movable bodily to open the hole.

17. In a slub catcher, two coacting members, one having a yarn receiving slot and the other comprising a lever pivoted on an axis substantially parallel with said slot, and a disc pivoted to said lever and having a graduated peripheral surface disposed lengthwise along said slot to form a yarn clearing hole, said disc being rotatively ad-

justable to change the size of the hole and movable bodily to open the hole, said yarn receiving slot being inclined for deflecting the yarn as it enters the slot to require the opening of the hole for the proper threading of the yarn.

18. In a slub catcher, two coacting members, one having a yarn receiving slot and the other comprising a lever pivoted on an axis substantially parallel with said slot, a disc pivoted to said lever and having a graduated peripheral surface disposed lengthwise along said slot to form a yarn clearing hole, said disc being rotatively adjustable to change the size of the hole and movable bodily to open the hole, and means for yieldingly holding the members together.

19. In a slub catcher, two coacting members, one having a yarn receiving slot and the other comprising a lever pivoted on an axis substantially parallel with said slot, a disc pivoted to said lever and having a graduated peripheral surface disposed lengthwise along said slot to form a yarn clearing hole, said disc being rotatively adjustable to change the size of the hole and movable bodily to open the hole, said yarn receiving slot being inclined for deflecting the yarn as it enters the slot to require the opening of the hole for the proper threading of the yarn, and means for yieldingly holding the members together.

20. In a slub catcher, two coacting members, one having a yarn receiving slot and the other having a graduated surface disposed lengthwise along said slot to form a yarn clearing hole, the last named member being movable to bring different portions of said graduated surface within said slot to change the size of the hole, and means for deflecting the yarn as it enters the slot to require the opening of the hole for the proper threading of the yarn.

In testimony, that I claim the foregoing as my invention, I have signed my name this 14th day of October, 1922.

JOHN O. McKEAN.
